UNITED STATES PATENT OFFICE.

JOHN W. COWELL, OF GRAND RAPIDS, MICHIGAN.

ADJUSTABLE TOOL-HANDLE.

1,177,604.

Specification of Letters Patent.

Patented Apr. 4, 1916.

Application filed November 7, 1914. Serial No. 870,758.

To all whom it may concern:

Be it known that I, JOHN W. COWELL, a citizen of the United States, residing at Grand Rapids, in the county of Kent and State of Michigan, have invented certain new and useful Improvements in Adjustable Tool-Handles, of which the following is a specification.

My invention relates to hand tools and particularly to the handles thereof.

The main object in view is to provide a construction of hand tool such, for instance, as a screw driver having a handle that can be adjusted to serve as a lever or angle handle if power greater than is usually necessary is required for the work, and so that greater leverage may be afforded in the operation of a tool of this nature when desired.

Another object is to provide a pivoted handle for a hand tool and adjustable means to fasten the handle normally against pivotal movement and in alignment with the tool proper.

A further object is to provide a spring controlled slidable ferrule and coöperating detail structure of the tool as the handle fastening means referred to.

With the foregoing as well as additional objects such as will later appear, in view, the invention has been embodied in several approved forms is illustrated in accompanying drawings forming a part thereof.

In said drawings:—Figure 1 is an elevation partly in section of one form of tool embodying my invention. Fig. 2 is a view similar to Fig. 1 but partly broken away and taken at a right angle thereto. Fig. 3 is a side elevation of a modified form, with the handle arranged in position at a right angle to the remainder of the tool. Fig. 4 is a view partly in side elevation and partly in section of a second modified form.

Referring specifically to the drawings, wherein like reference characters designate like or similar parts, and first to the device of Figs. 1 and 2, numeral 1 designates a screw-driving shank. While the tool shown is a screw driver it is to be understood that my improvements are not limited to use in connection with such a tool as it can equally well be applied to any tool having a shank or other part to be turned. This shank 1 is integral with a second and larger shank 2 forming therewith the turning body of the

tool. A shoulder or abutment 3 is provided at the junction of the shanks.

The body 1—2 at its upper end is bifurcated a suitable distance to provide a slot 4 and arms 5. A suitable form of handle 6 is provided, having a reduced lock leg 7. This leg 7 is normally within the slot 4 and the handle as a whole is mounted for pivotal movement by a pivot pin 8 passing through the arms 5 and the leg. The movement of the handle, however, is limited through the provision of abutment shoulders 9 and 10 respectively on the shank 2 and handle 6 which engage when the handle and body are in positions at right angles to each other. Leg 7 may itself serve as a tool and to this end its free end is suitably shaped, for instance to form a pick or punch 11. It will be noted from Fig. 1 that the leg 7 or punch 11 extends below the shoulder 3.

Normally the handle 6 is locked in alignment with the body 1—2 and to this end an approved locking member is provided. As shown this locking member may be a sleeve or ferrule 12 slidable longitudinally on shank 1. A recess 13 is provided within the ferrule in which is housed a coil spring 14 engaging the shoulder of the ferrule in the inner end of the recess and pressing the ferrule into abutment with the shoulder 3. A seat for the spring at its lowermost end is provided in the form of a collar or laterally projecting member 15 removably fastened to shank 1 by a set screw 16. This collar 15 extends part-way into the recess 13 and serves as a guide for the ferrule.

If the device is to be used as an ordinary screw driver, the parts will be in position shown in Fig. 1, where it will be noted the locking ferrule 12 overlaps the leg 7, preventing swinging movement thereof. Should greater leverage be required or desired, the ferrule 12 is depressed against the tension of spring 14 and the handle 6 tilted and swung on its pivot to the horizontal position shown in dotted lines in Fig. 1 so that it may serve as a lever to enable easier and more advantageous turning of the body 1—2. Abutment shoulders 9 and 10 engage when the handle is at right angles to the body as the grip end of the handle is larger and heavier than leg 7, the handle will seek this position unless locked. When the handle is returned to locked position, ferrule 12 is first de-

pressed and held against the tension of spring 14 leg 7 then moved into the slot 4 and the ferrule then released whereupon the spring restores it to the position shown in Figs. 1 and 2, overlapping and locking the leg 7 and handle.

It is to be realized that the form described is but one embodiment of the invention and that the details of construction may be varied without departing from the spirit and scope of my invention. For instance, modified forms are shown in Figs. 3 and 4, which embody slight changes in construction although the principle of operation remains the same. In Fig. 3 the shank 20 which is the equivalent of ferrule 12, extends close to the handle and the handle 22 is of different shape, having a much shorter locking leg 23 and a different shaped tool end 24. As regards Fig. 4, the screw driving shank is designated 30, a lateral enlargement equivalent to collar 15 is shown at 31, the ferrule is 32, the spring 33, the second shank 34, its arms 35 and slot 26.

The handle has a short locking leg 37 joined to the arms 35 by a pivot pin 38, and has a blade 39 integral with the leg 37 and to which grip sections 40 are fastened by rivets 41. When the ferrule 32 is depressed, the handle is moved to horizontal position and the ferrule then released. In this form as in Fig. 3, the handle on both sides of the pivot rest on the ferrule so as to prevent pivotal movement of the handle without shifting of the ferrule.

35

I claim:

The combination of a body, a handle pivoted thereto and provided with a tool, and a spring pressed ferrule slidable to overlap the tool to fasten the tool and handle against pivotal movement relative to the body.

In testimony whereof I affix my signature in presence of two witnesses.

JOHN W. COWELL.
